(Cl. D44—29)

To all whom it may concern:

Be it known that I, Max N. Mossel, a citizen of the United States, residing at Fulton, in the county of Callaway and State of Missouri, have invented a new, original, and ornamental Design, for a Combined Corn-on-Cob Butterer and Salter, of which the following is a specification, reference being had to the accompanying drawings, forming part thereof, in which:

Fig. 1 is a top perspective view of a combined corn-on-cob butterer and salter, embodying my new design,

Fig. 2 is a bottom perspective view,

Fig. 3 is a plan view,

Fig. 4 is a side elevational view,

Fig. 5 is a bottom plan view,

Fig. 6 is a front elevational view, and
Fig. 7 is a back elevational view.

I claim:

The ornamental design for a corn-on-cob butterer and salter, substantially as shown.

MAX N. MOSSEL.
